United States Patent Office.

LAVINIA H. FOY, OF WORCESTER, MASSACHUSETTS.

Letters Patent No. 63,625, dated April 9, 1867.

IMPROVEMENT IN PINS FOR THE ATTACHMENT OF BOWS AND ROSETTES.

The Schedule referred to in these Letters Patent and making part of the same.

KNOW ALL MEN BY THESE PRESENTS:

That I, LAVINIA H. Foy, of the city and county of Worcester, and State of Massachusetts, have invented certain new and useful Improvements in Bow and Rosette Pins; and I do hereby declare that the following is a full, clear, and exact description of the same, reference being had to the accompanying drawings, forming a part of this specification, in which—

Figure 1 represents a front view of a bow attached by one of my improved pins.

Figure 2 represents a perspective view of my improved pin; and

Figure 3 represents a longitudinal section of my improved pin, and the bow shown in fig. 1.

In the drawings, A represents the body or frame part of the device, which has a pin, a, hinged to one end, as seen at b, and a hook, c, attached at the other end to receive the point d of pin a. Upon the other side of body A is hinged another pin, e, as seen at f, while a shield, g, is attached to the end of frame A to receive the point of pin e, as fully shown in figs. 2 and 3 of the accompanying drawings. This shield prevents all injury to the fingers while attaching the bow to the collar or dress. The device is shown applied to use in fig. 1 in securing the bow B to C, in which case it will be observed that the device is entirely covered and shielded from view, while at the same time the bow B is sustained in a secure and proper position, and that, too, without either of the ends D D or bows E E being fastened or so attached as to interfere with their neat appearance.

By reference to fig. 3 of the drawings it will be seen that the pin e is passed through the central part of the back of the bow, and the point h sprung under the shield g, and then the bow is fastened or secured to the collar or dress by means of the pin a on the other side of the bar or frame of the pin. The usual mode of attaching bows or rosettes is to pin them on, in which case two common pins are used, which cannot be applied without considerable inconvenience. Again, when attached by means of common pins, the ends D and bows E, or one of each at least, are so confined as to have a stiff appearance. All of the above objections are entirely obviated by my invention, which greatly facilitates the fastening and arranging of bows and rosettes, either upon a lady's collar, dress, or head. The article can also be used to advantage by gentlemen in connection with their cravats. The pins a and e may be so arranged as to stand at any desired angle with each other, in which case the bar or frame A would be in the form of a cross, so as to properly support the pins and the shield g and hook e. I prefer, however, to make the pin as shown in the drawings.

Having described my improvement, what I claim as of my invention, and desire to secure by Letters Patent as an improved article of manufacture, is—

A bow and rosette pin, constructed substantially as shown and described

LAVINIA H. FOY.
